TWISTING APPARATUS

Estyle D. Hanson, George E. Henning, and Oscar G. Nelson, Baltimore, Md., assignors to Western Electric Company, Incorporated, New York, N. Y., a corporation of New York

Application October 18, 1946, Serial No. 704,132

8 Claims. (Cl. 57—13)

1

This invention relates to twisting apparatus and more particularly to flyer type twisting apparatus for forming multiconductor cordage of the type used extensively in communication equipment.

Many types of multiconductor cords and cables are used in the communication field. Also it is sometimes desirable to use a plurality of insulated conductors that are twisted together into groups, usually in pairs. In the manufacture of communication cords and cables, the conductors frequently are twisted together to form a core over which is applied a suitable jacket made of a vulcanized material, such as a rubber or synthetic rubber-like compound, or of a suitable textile material, such as a braid.

Various types of apparatus have been designed for twisting conductors together to form cordage or cores of cables, or to form groups of individually insulated conductors. It is desirable that such twisting apparatus be as compact as possible, and that means be provided therein for advancing the conductors therethrough at a uniform rate and without slippage. It is also important that the various elements of the apparatus be so designed that the desired type of twisting is accomplished. It is particularly important in twisting apparatus used to make what is known as "close spiral," flexible cordage that no slippage occurs as the conductors are being twisted together, and that the point at which the twist is given to the conductors be controlled accurately.

An object of the invention is to provide a new and improved twisting apparatus.

One type of twisting apparatus embodying the invention comprises a horizontal type flyer unit rotatable about its central axis and having a twisting head thereon for twisting together a plurality of conductors to form a composite core, means for serving a textile covering around the composite core to form a core unit, a pair of driven capstans disposed within the flyer unit for advancing the conductors to the twisting head, means on the central axis of the flyer unit for supporting a takeup reel, and traversing means carried by the flyer unit for distributing the composite core unit in even layers on the takeup reel.

A clear understanding of the invention may be obtained from the following detailed description of a specific embodiment thereof, when read in conjunction with the accompanying drawings, in which:

Fig. 1 is a side elevation of a portion of a twist-

2

ing apparatus forming a specific embodiment of the invention;

Fig. 2 is a side elevation constituting a continuation of Fig. 1 and showing the remaining portion of the apparatus;

Fig. 3 is an enlarged, fragmentary, vertical, sectional view of a portion of the apparatus shown in Fig. 2;

Fig. 4 is an enlarged, vertical, sectional view taken along line 4—4 of Fig. 1;

Fig. 5 is an enlarged, fragmentary, sectional view taken along line 5—5 of Fig. 1;

Fig. 6 is an enlarged, vertical, sectional view of a portion of the apparatus shown in Fig. 1, and

Fig. 7 is an enlarged, fragmentary view of the apparatus shown in Fig. 6.

The twisting apparatus described hereinbelow is designed to form four-conductor close spiral cordage. However, this apparatus may be modified to form various types of multiconductor cordage and cables.

Referring to the drawings, it will be noted by reference to Fig. 1, that a plurality of individually insulated conductors 10—10 (in this case four) 25 are being withdrawn from a suitable supply (not shown) and directed over a plurality of rotatable guide pulleys 12—12 forming part of a guide unit 11, which pulleys direct the conductors 10—10 sharply toward a twisting head 13 provided on a 30 rotatable flyer unit 14. The twisting head 13 is rotatable with the flyer unit 14 and twists the conductors 10—10 together spirally around a textile cord 15 so as to form a composite core 16. The core 16 is advanced through a central aperture provided in a serving head 17 by the aid of which a textile covering is served around the composite core 16 to form a textile covered core unit 18.

The core unit 18 next advances through an 40 elongated bore provided in a trunnion 19 formed integrally with the flyer unit 14 and then is directed to a pair of driven capstans 20 and 21 spacedly positioned in the flyer. The core unit 18 passes alternately around substantial portions 45 of the peripheries of the capstans 20 and 21 (Fig. 1) a predetermined number of times and then is directed from the capstan 20 directly to a guide pulley 22 provided on the opposite side of the flyer unit 14. The core unit 18 passes directly 50 from the pulley 22 to a pulley 23 rotatably mounted on a distributor nut 24, which serves to distribute the core unit 18 evenly on a reel 25 rotatably supported within the flyer unit 14 and along the central axis thereof.

55 The guide unit 11 (Figs. 1 and 7) comprises a

plate 26 adjustably positioned on supports 27-27 rigidly secured on a base plate 28 of the serving head 17. This arrangement facilitates the positioning of the pulleys 12-12 close to the end of the twisting head 13 so that each of the conductors 10-10 approaches the twisting head 13 at a relatively sharp angle. A restraining member 29 is adjustably positioned on the central axis of the guiding unit 11 and has a conical end 30 provided therein for engaging the conductors 10-10 at the point at which they are twisted together and serves to hold the twisting point at a fixed point with respect to the pulleys 12-12 and the twisting head 13. By positioning the pulleys 12-12 close to the twisting head, the twisting head is able to twist the conductors together so that the individual spirals of the core 16 formed thereby lay against each other throughout the core. By holding the twisting point in a fixed position, a uniform twist is imparted to the conductors throughout the core. The serving head 17 consists of a rotor 31 rotatably mounted on a hub 32 centrally secured on the base plate 27. A plurality of strand supply cops 33-33 are rotatably mounted on the rotor from which strands 34-34 are withdrawn and served spirally around the composite core 16 to form the textile covered core unit 18 when the rotor is rotated. A more complete description of the conductor guiding member 11 and the serving head 17 is given in copending application Serial No. 704,157, filed October 18, 1946, now Patent No. 2,475,427, July 5, 1949, by G. E. Henning.

The flyer unit 14 (Figs. 1, 2 and 4) consists of a pair of spaced end members 35 and 36 and a pair of elongated tubular support members 37 and 38, which have their extremities securely clamped to the extremities of the end members 35 and 36 to form a rigid rectangular frame. The flyer unit 14 is rotatably mounted between a pair of spaced standards 40 and 41 provided on the frame of the apparatus by means of the hollow trunnion 19 formed integrally with the end member 35 and a hollow trunnion 42 formed integrally with the end member 36. The trunnion 42 has a sprocket 43 keyed thereto which engages a chain belt 44 connected to a sprocket 45 keyed to a motor shaft 46 driven by a main motor 47. The motor 47 is arranged to drive the flyer unit 14 in a clockwise direction as indicated by the arrow (Fig. 4), which direction twists the conductors 10-10 tightly together so that the spirals of the individual conductors lay against each other in the twisted core 16 and are formed in the direction shown in Fig. 7. The shaft 46 extends over and drives a change gear mechanism 50 and a variable speed reducer 51. The speed reducer 51 is arranged to rotate the serving head rotor 31 by means of a belt 52 and a pulley 53 keyed thereto in the same direction as the flyer unit 14, but at a rate of speed substantially greater than that of the flyer unit thereby enabling the rotor 31 to spirally serve the strands 34-34 around the rotating core 16.

A housing 55 (Figs. 1 and 4) integrally formed on the upper end of the end member 35 has formed therein an upper circular depression 56, a lower circular depression 57 and a bore 60 in the wall section of the housing 55 between the depressions 56 and 57. A stud 61, having a short body portion 62, a shoulder portion 63 and a long body portion 64 is positioned in a bore 66 centrally provided in each of the depressions 56 and 57. The extremity of the body portion 62 of the stud 61 is threaded to receive a nut 67, whereby the

stud 61 may be rigidly secured to the housing 55 so that the body portion 64 is centrally positioned within its associated depression.

The capstan 20 is rotatably mounted on the body portion 64 of the stud 61 positioned in the depression 57 by a pair of annular bearings 71-71 positioned in counterbores provided on a hub portion 72 of the capstan 20. The periphery of the capstan 20 is provided with four semi-circular grooves 73-73 arranged to receive the core unit 18 as it passes around the capstans 20 and 21 on its way to the takeup reel 25. The capstan 21 is rotatably mounted on the body portion 64 of the stud 61 secured in the circular depression 56 in the same manner described above for the capstan 20. The capstan 21, however, has only three semicircular grooves 76-76 provided on its periphery for directing the core unit 18 to the takeup reel 25.

The core unit 18 passes through a central bore 79 provided in a trunnion 19 of the end member 35 (Fig. 4) and enters the left hand groove 73 of the capstan 20, passes around the lower portion of this groove and then is directed under the capstan 21 and into the left hand groove 76 of the capstan 21 and around the upper portion of the groove 76. The core unit 18 is directed from the groove 76 into the second groove 73 of the capstan 20, and so on until the core unit 18 passes alternately around the lower portion of the second and third grooves of the capstan 20 and around the upper portion of the second and third grooves of the capstan 21. The core unit 18 then passes from the third groove of the capstan 21 into the fourth groove provided in the capstan 20, which groove is vertically aligned with a peripheral groove provided on the pulley 22. The semicircular grooves 73-73 and 76-76 are spaced on the face of the capstans 20 and 21, respectively, so as to prevent the various portions of the core unit 18 from rubbing against each other, as the core unit passes alternately back and forth around portions of the capstans 20 and 21, and to provide the maximum contacting surface between the core unit 18 and the capstans.

The capstan 20 is provided with a flange 77, which slidably engages the face of the wall of the circular depression 57 and a felt ring 78 seated in an annular groove 80 provided in the face of the aforementioned wall. The capstan 21 is provided with a hub portion 81, which likewise slidably engages the face of the wall of the depression 56 and a felt ring 82 positioned in an annular groove 83 provided in the wall. The capstans 20 and 21 are maintained on the body portion 64 of their respective studs 61-61 by means of nuts threaded on the ends of the body portions and are thereby maintained against the felt rings 78 and 82 positioned in the walls of the depressions 56 and 57. A bevelled ring gear 84 is centrally positioned on each of the capstans 20 and 21 (Figs. 1 and 4), and each ring gear meshes with a bevelled pinion 85 secured on the extremities of a shaft 86 rotatably mounted in the vertical bore 60 by antifriction bearings 87-87 positioned in counterbores located at opposite ends of the bore 60.

The ring gear 84 positioned on the capstan 20 also meshes with a bevelled pinion 90 positioned within the depression 57 and secured on the end of a shaft 91 freely rotatable in the housing 55 and extending horizontally from the depression 57 so that its left end projects beyond the left side of the end member 35. A pinion 92 is se-

cured on the left end of the shaft 81 which pinion 92 meshes with an idler gear 93 rotatably mounted on the left hand face of the end member 35. The idler gear 93 in turn meshes with a ring gear 94 rotatably mounted on the trunnion 19 between the standard 41 and the end member 35. A sprocket 95 is keyed on the hub of the ring gear 94 and engages a chain belt 96 connected to an output sprocket of the change gear mechanism 50 which receives its power from the motor 47 through the shaft 46.

The system of gears 92, 93 and 94 (Figs. 1 and 4) is arranged to cooperate with the bevelled pinion 90, which engages the bevelled ring gear 84 secured to the capstan 20, and drives the capstan 20 in a counterclockwise direction, as indicated by the arrow thereon, at a constant rate of speed. The capstan 20 in turn drives the capstan 21 in a clockwise direction by means of the bevelled pinions 85-85 secured on the shaft 86 and the bevelled ring gear 84 secured on the capstan 21. Obviously, the system of gears including the gear 93 may be arranged to rotate the capstans in the proper direction when the flyer is rotated faster or slower than the ring gear 94 driven by the change gear mechanism 50.

By virtue of the fact that the capstans are driven in the opposite directions, it is evident that the capstan 20 tends to force the core unit 18 tightly in the semicircular grooves 76-76 provided in the periphery of the capstan 21, and likewise the capstan 21 tends to force the core unit 18 tightly within the semicircular grooves 73-73 of the capstan 20, in which case each capstan is tending to aid the companion capstan in obtaining a tight grip on the core unit 18, and thus advance it through the twisting head 13 at the desired rate of speed. The alternating arrangement of the core unit 18 as it passes from capstan 20 to capstan 21 and vice versa serves to prevent the core unit from slipping in the semicircular grooves of the capstans as the flyer unit 14 twists the conductors 10-10 together to form the close spiral composite core 16.

After the core unit 18 passes back and forth over the capstans 20 and 21 in the manner described above, it is directed to the guide pulley 22 and thence to the pulley 23 rotatably mounted on the distributor nut 24, which pulley serves to lay the core unit 18 evenly on the winding surface of the takeup reel 25. The nut 24 is slidably mounted on the tubular support 38 and a rod 97 mounted parallel to the support 38 and is caused to reciprocate between the flanges of the takeup reel 25 by a traversing mechanism presently to be described.

The ring gear 94 rotatably mounted on the trunnion 18 also engages an idler gear 100 secured on the end of a shaft 101 rotatably mounted in a suitable boss provided on the end member 35 and having a pinion 102 secured on the opposite end thereof. The pinion 102 engages an idler gear 103 secured on the end of a shaft 104 rotatably mounted in the end member 35 and having an idler pinion 105 secured on the opposite end thereof. The idler pinion 105 meshes with an idler gear 106 rotatably mounted on the end member 35, which idler gear meshes with a gear 107 secured on the end of a traversing shaft 110 which is rotatably mounted within the tubular support 38 of the flyer unit 14. The shaft 110 is provided with an enlarged body portion 111 having a conventional traversing thread 112 (Fig. 5) cut therein.

The traversing thread 112 slidably engages the

arcuate-shaped end of a finger 113 (Fig. 4) secured to a cylindrical body portion 114 of a thread follower 115. The body portion 114 is slidably positioned in a bore 116 provided in a body portion 117 of the distributor nut 24. The arcuate-shaped end of the finger 113 is maintained in engagement with the traversing thread 112 by a spring 118 positioned between the body 114 and the end of a nut 120 threadedly mounted in the end of the bore 116. A pair of spaced supports 121-121 are formed on the body portion 117 so as to straddle the nut 120 and have horizontally aligned bores 122-122 provided therethrough for receiving self-lubricating bushings 123-123. The bushings 123-123 slidably engage the rod 97 mounted in a parallel position with respect to the support 38 by means of a bracket 130 formed integrally with the end member 36 and a bracket 131 secured to the vertical leg of an angle-shaped support 132 formed integrally with the end member 35. The tubular support 38 has a portion of its wall cut away between the bracket 131 and the bracket 130 to provide an opening 129 in which the finger 113 rides as the follower 115 and the nut 24 are reciprocated as a result of the rotation of the shaft 110 and the traversing thread 112.

The system of gears comprising the gears 100, 102, 103, 105, 106 and 107 (Figs. 1 and 4) is arranged to rotate the shaft 110 and its traversing thread 112 at a speed which will reciprocate the distributor nut 24 at a rate which will lay a given size core unit, such as the core unit 18 being advanced at a given rate of speed by the capstans 20 and 21 evenly across the winding diameter of the takeup reel 25. Obviously, this system of gears may be arranged to suit the particular size of the unit to be distributed on the takeup reel, and also to suit any change in the rate at which the unit is being advanced by the capstans 20 and 21.

The system of gears mounted on the left face of the end member 35 is enclosed by a housing 133 (Fig. 1) formed integrally with the end member and a cover plate 134 removably secured to the housing. Likewise, the intermediate idler gears 102 and 103 are enclosed by a housing 135 formed integrally with the lower end member 30 and a cover 136 removably secured on the housing 135. The housings and their respective covers serve to retain a quantity of lubricant around the gears enclosed thereby and further prevent the lubricant from flying off the gears as the flyer unit 14 is rotated. In addition, the housing 135 prevents the gear lubricant from getting on the core unit 18 as it is advanced into the flyer unit and as it passes around the capstans 20 and 21 disposed therein.

The support 132 is provided with a hub portion 137 (Fig. 1) which is aligned with the central axis of the flyer unit 14 and has a rotatable center 138 designed to engage a central tapered bore (not shown) provided in the left hand side of the takeup reel 25. The right hand side of the takeup reel 25 is supported by a tapered center 140 formed integrally with an annular flange 141 rigidly secured on the end of a reel driving shaft 142. The flange 141 is provided with a spring-pressed plunger 143 which engages a hole (not shown) provided in the right hand flange of the takeup reel 25 to drive the takeup reel 25 when the shaft 142 is rotated. The shaft 142 extends horizontally through the standard 41 and has secured on the opposite end thereof a differential gear mechanism 145 (Fig. 2) whose operation is controlled

by an externally disposed induction type torque motor 146. The shaft 142 is driven by the combined action of the motor 47 which drives the flyer unit 14 and the torque motor 146 which controls the operation of the differential gear mechanism 145, so that as the winding operation of the reel proceeds from the empty reel to a full reel, the speed of rotation of the reel progressively decreases so as to maintain uniform tension on the core unit 18 as it is taken up by the reel.

For a more complete understanding as to how the combined operation of the main driving motor 47 and the differential gear mechanism 145 provides constant tension on the core unit 18 being taken up by the reel 25, attention is directed to G. E. Henning et al. Patent 2,338,848, issued January 11, 1944. Inasmuch as the differential gear mechanism 145, included in the present disclosure, operates in a manner identical with that described in the above-mentioned patent, it is believed that further description of the operation of this apparatus is not required.

It should be noted that since the core unit 18 is distributed on the takeup reel 25 by the traversing thread 111 and the distributor nut 24 mounted on the flyer unit, it is not necessary to reciprocate the shaft 142 in the manner described in the above-mentioned patent in order to distribute the core unit 18 evenly on the reel. However, in order to insert an empty reel in the flyer unit 14 or to remove a full reel from the flyer unit, it is necessary that the shaft 142 be manually reciprocable to the extent that the tapered end 140 may be propelled or repelled sufficiently to permit such operations to be performed on the reel 25. To accomplish the required reciprocation of the shaft 142, a propelling and repelling mechanism 150 (Figs. 2 and 3) is rigidly secured on the end of a hub 151 provided on a member 152 forming a part of the differential gear mechanism 145.

The propelling and repelling mechanism 150 (Figs. 2 and 3) consists of a support 156 rigidly secured on the hub 151 by means of a counterbore 155 provided on one end thereof and has a bore 157 provided therein substantially equal to the diameter of the shaft 142. A nut 160 is slidably positioned within the bore 157 and is provided with an internal thread 161 which engages a threaded stud 162 rotatably secured on the free end of the shaft 142. A ring 163 is mounted on the end of the support 156 and is provided with a bore therethrough which is substantially smaller than the bore 157, thereby causing an annular portion thereof to project inwardly beyond the bore 157 provided in the support 156, and engage a peripheral shoulder 164 formed on a tubular body portion 165 of the nut 160. The right face of the ring 163 is provided with a plurality of V-shaped teeth 166-166 designed to engage identically shaped teeth 167-167 provided on the left face of a retractable ring 170.

The teeth 167-167 of the ring 170 are maintained in engagement with the teeth 166-166 of the ring 163 by a plurality of springs 171-171 positioned between the right face of the ring 170 and the bottom of counterbores 172-172 provided in a hub portion 173 of a hand wheel 174 keyed on the body portion 165 of the nut 160. The ring 170 may be withdrawn from engagement with the ring 163 by means of a knob 176 rotatably mounted in a bore provided in an annular flange member 177 against the outer face of the hub 173 of the hand wheel 174. The flange 177 has a plurality of studs 180-180 secured equidistantly around its periphery which slidably engage and

extend through complementary bores 181-181 provided in the hub 173 to horizontally aligned bores provided in the ring 170, in which the bores of the ends of the studs 180-180 are rigidly secured.

5 A ring 185 is rigidly secured in the counterbore 155 and is provided with an ear 186 which projects inwardly from the bore therethrough and slidably engages a groove 187 cut in the stud 162. The stud 162 is rotatably mounted in the end of the shaft 142 because the mechanism 150 is driven directly by the flyer unit 14 at a constant rate of speed while the speed of rotation of the shaft 142 must vary as the winding diameter of the takeup reel increases from an empty reel to a full reel. The ring 186 serves to prevent rotation of the stud 162 with respect to the support 156 when the nut 162 is rotated by a turning motion of the hand wheel 174. When the hand wheel 174 is turned in a clockwise direction, the shaft 142 and the reel engaging center 140 secured on the end thereof are moved to the left, and vice versa (Figs. 1, 2 and 3).

25 The teeth 166 and 167 are arranged on the faces of the rings 163 and 170, respectively, so that there will be a slipping, ratchet-action between the rings 163 and 170 when the hand wheel 174 is rotated in a clockwise direction (Fig. 3), thereby causing the center 140 to move to the left and engage the center hole of the takeup reel 25, but will lock with each other and prevent the hand wheel from being rotated in a counterclockwise direction to retract the center 140 from the reel 25 unless the knob 176 is first actuated to draw the ring 170 toward the hub 173 of the hand wheel 30 against the action of the compression springs 171-171. The teeth 166-166 and 167-167 serve as a latch arrangement for the hand wheel 174 and prevent rotation thereof when the hand wheel is being rotated with the flyer unit 14 and the differential gear mechanism 145. This is in effect a safety feature which prevents the hand wheel from being rotated to repel the shaft 142 so as to retract the center 140 from the reel 25 during the operation of the flyer.

45 Since a one-direction slipping action is provided between the support 156 and the hand wheel 174, it is believed to be obvious that when the support 156 first starts to rotate with the flyer, the hand wheel 174 possesses such mass that it will slip and lag behind the support when it starts to rotate. Likewise, if the hand wheel is being rotated with the support 156 and the flyer and support are brought to a substantially sudden stop, the hand wheel will develop such inertia that 50 it will continue to rotate until the slipping friction of the rings 163 and 170 overcome the inertia thereof. In the first case, the slipping of the hand wheel will draw the reel shaft to the left and thereby disengage or partially disengage the center 140 from the reel. In the second case, the continued rotation of the hand wheel will drive the center 140 hard into the reel and thereby make disengagement of the center from the reel 55 very difficult.

60 65 To overcome this condition, a stud 190 is threadedly mounted in a tapped bore provided in the knob 176 (Fig. 3) and has secured on the end thereof a cylindrical head 191 arranged to move freely in the tubular body portion 165. A ring 192 is secured in the end of the tubular body portion 165 of the nut 160 and is provided with a internally disposed ear 193 which slidably engages a longitudinal groove 194 cut in the stud 190, thereby preventing the stud 190 and the head 191 from turning when the knob 176 is turned.

It is believed to be apparent from the above description that the hand wheel 174 cannot be turned in either direction and therefore no slipping action can occur between the hand wheel 174 and the support 156 when the head 191 is clamped tightly against the left face of the ring 192 by the knob 176 and the stud 190. This is due to the fact that when the knob 176 is turned in a clockwise direction, it draws the stud 190 to the right which causes the head 191 to abut to the ring 192 and thereby clamp the flange 177 tightly against the hub 173 of the hand wheel 174. To place the hand wheel 174 and the ring 170 in a rotatable condition, the knob 176 must first be turned in a counterclockwise direction until the stud 190 and its head 191 are moved to the left a distance sufficient to permit the ring 170 to be retracted by the knob against the action of the springs 171-171 and thereby disengage its teeth 167 from the teeth 166 on the ring 163.

A spring 195 is positioned in the tubular body portion 165 between the end of the stud 162 and the head 191 and surrounds a post 196 secured to the head 191 and extending therefrom into a bore provided in the end of the stud 162. The spring 195 serves to take up any backlash in the threaded connection between the nut 160 and the stud 162.

A pair of curved supports 200-200 (Figs. 1 and 4) are spacedly positioned on the flyer unit 14 so as to engage the periphery of the flanges of the takeup reel 25. The supports are provided only as a means for temporarily supporting the reel in the flyer during the loading and unloading of the reel therein. The curved supports are arranged to support the reel in the flyer when the tubular members 37 and 38 are horizontally aligned with the rotating axis of the flyer so that the central apertures of the reel 25 (not shown) are almost in line with the tapered reel supporting centers 137 and 140.

By supporting the reel in this manner, the tapered center 140, as it is moved to the left by rotation of the hand wheel 174, will engage the respective reel aperture and drive the reel to the left until the opposite central aperture properly engages the tapered center 137 whereupon the reel is automatically lifted off the supports 200-200 and becomes rotatably supported in the flyer. When it is desired to remove the reel from the flyer, the flyer must be positioned so the supports will be under the reel, whereupon the center 140 may be withdrawn from the reel aperture thereby letting the reel drop gradually onto the supports, from which the reel may be removed by suitable hoisting means.

The above-described twisting apparatus operates as follows:

Assuming that the reel driving shaft 142 has been repelled by the hand wheel 174 so as to retract the center 140 to its outermost position, an empty reel 25 is positioned on the supports 200-200 and the hand wheel is manually rotated in a clockwise direction until the reel is rotatably positioned on the supporting centers 134 and 140. It will be assumed that a plurality of conductors, such as conductors 10-10 have been drawn from a suitable supply (not shown) and positioned over the guide rollers 12-12, threaded through the bore provided in the twisting head 13 and the trunnion 19 together with the cord 15 to the capstans 20 and 21, and passed alternately around the periphery of the capstans 20 and 21, from the capstan 20 to the guide pulley 22 and thence to the pulley 23 angularly mounted on the dis-

tributor nut 24 from which the conductors 10-10 and the cord 15 are directed and secured to the takeup reel 25.

The motor 47 is then energized by suitable control means (not shown) to place the entire twisting apparatus in operation, that is, the flyer 14, the capstans 20 and 21, the distributing nut 24 and the serving head 17 all are operating in timed relation with respect to each other. The capstans 20 and 21 advance the conductors 10-10 continuously over the guide pulleys 12-12 positioned on the guiding member 11 so as to direct the conductors at an acute angle toward the twisting head 13. The twisting head 13, which rotates with the flyer 14, grips the conductors 10-10 tightly and causes them to be twisted around the cord 15. The guide pulleys 12-12 are arranged adjacent to the twisting head so that the twisting action imparted to each of the conductors is checked by its respective guide pulley, thereby causing the conductors to be twisted tightly together at a point close to the twisting head.

The position of the restraining member 29 is adjusted so that its conical end 30 engages the conductors 10-10 at the twisting point, thereby preventing the twisting point from surging back and forth between the conical end 30 and the twisting head 13. This arrangement of the guide pulleys and the restraining member with respect to the twisting head causes the conductors to be twisted together to form the composite close spiral core 16 (Fig. 7). The speed of rotation of the flyer unit 14 and the speed at which the capstans 20 and 21 are driven are so arranged with respect to each other, that the flyer 14 by means of its twisting head 13 will form the close spiral core 16, that is, the spirals formed by the individual conductors 10-10 will lay against each other throughout the entire length of the core 16.

The capstans 20 and 21 are driven by the change gear mechanism 50 at the proper rate of speed and in the proper direction to advance the core 16 to a serving head 17 by means of which the strands 34-34 are spirally served around the composite core 16 to form the textile covered core unit 18. The core unit 18 is passed alternately around substantial portions of the peripheries of the capstans 20 and 21 in order to secure good traction between the capstans and the core unit 18. The core unit 18 passes from the capstan 20 to the guide pulley 22 and thence to the pulley 23 rotatably mounted on the distributor nut 24. The traversing shaft 110 is also driven by the change gear mechanism 50 and in timed relation with the speed at which the capstans 20 and 21 are driven so that the core unit 18 will be evenly distributed on the reel 25.

Due to the fact that the core unit 18 is being delivered by the capstans 20 and 21 and the distributor nut 24 and the reel 25 at a constant rate, it is necessary that the reel 25 be rotated at a correspondingly decreasing speed as the winding diameter of the reel increases from an empty reel to a full reel. The tension on the core unit 18 being taken up by the reel 25 must remain substantially constant throughout the winding operation of the reel from an empty reel to a full reel. To accomplish this result, the reel driving shaft 142 is driven jointly by the flyer unit 14 and the differential gear mechanism 145, the operation of which is controlled by the induction type torque motor 146. The characteristics of the motor 146 are such that, as its speed decreases, its torque increases, and it is this char-

acteristic of the torque motor that is utilized to maintain a constant tension on the core unit 18 being taken up by the reel 25.

The above-described flyer unit possesses several distinct advantages over flyer units in use heretofore. First, since the twisting head 13 of the flyer unit 14 must grip the core unit 18 very tightly in order to twist the conductors 10-10 together in such manner as to form a close spiral core, it is necessary to provide a pair of driven capstans on the flyer to obtain the pull on the core unit 18 required to advance the core unit through the bore of the twisting head. In addition, the manner in which the core unit 18 is wrapped alternately around the peripheries of the capstans 20 and 21 provides the best traction obtainable from two capstans used to advance such a core unit 18 through the tight fitting bore of the twisting head 13.

Secondly, instead of providing externally disposed means for reciprocating a takeup reel back and forth within the flyer unit itself, which operation necessitates the use of considerable equipment and floor space, as well as requiring considerable power, the flyer unit 14 has the takeup reel 25 maintained in a stationary position with respect to lateral movement thereof. The core unit 18 is evenly distributed over the winding surface of the reel by means of the traversing shaft and the distributor nut 24 carried on the flyer itself. This type of flyer unit requires a minimum amount of floor space and will eliminate the need for externally disposed apparatus for reciprocating the takeup reel.

While the above-described apparatus is particularly adapted to twisting a plurality of insulated conductors together to form a close spiral core unit, it may be readily adapted to twist together various types of filamentary strands to form units suitable for many other purposes. Therefore, the invention is limited only by the scope of the appended claims.

What is claimed is:

1. An apparatus for twisting a plurality of conductors together to form a composite close spiral core, which comprises a flyer rotatable about its central axis, externally disposed means for rotating the flyer at a constant rate of speed, a tubular twisting head positioned on the flyer for twisting a plurality of conductors together, means associated with the twisting means for causing the conductors to be twisted into a composite close spiral core when the flyer is rotated, means positioned adjacent to the twisting means for serving a textile covering around the composite core to form a core unit, externally disposed means for rotating the serving means about the twisting head and the composite core, means for continuously advancing the core unit through the twisting means to advance the conductors to the twisting means, means disposed along the central axis of the flyer for rotatably supporting a takeup reel for the core unit being advanced through the twisting head including a fixed center for rotatably supporting one side of the reel and a rotatable shaft having its free end arranged to support the opposite side of the takeup reel, said shaft being provided with means adjacent the free end thereof for rotating the reel when the shaft is rotated, means for propelling and repelling the shaft along its axis to cause the supporting means and the reel rotating means to engage or disengage the reel as desired, means provided on the flyer for distributing the core unit evenly on the takeup reel, and means for

simultaneously driving the advancing means and the core distributing means in timed relation with respect to the speed of rotation of the flyer unit.

2. Twisting apparatus, which comprises a rotatable flyer unit, means associated with the flyer unit for twisting a plurality of conductors together, means provided in the flyer unit for rotatably supporting a takeup reel for the twisted conductors including a fixed center for rotatably supporting one side of the takeup reel, and a rotatable shaft having its free end arranged to support the other side of the reel and rotate the reel when the shaft is rotated, means for propelling and repelling the shaft to cause the supporting and driving end thereof to engage or disengage the reel as desired, and means for locking the propelling and repelling means when the end of the shaft is in engagement with the reel to prevent the propelling and repelling means from being operated by the rotation of the flyer.

3. Twisting apparatus, which comprises a rotatable flyer unit, means associated with the flyer unit for twisting a plurality of conductors together, means provided on the flyer unit for supporting a takeup reel for the twisted conductors including a fixed center for rotatably supporting one side of the takeup reel, a rotatable shaft having one end thereof arranged to support the other side of the reel and rotate the reel when the shaft is rotated, a differential gear mechanism rotatable with the flyer and arranged to effect a variable speed drive between the flyer and the shaft, a hand wheel mounted on the end of the differential gear mechanism and arranged to engage the other end of the shaft and cause the shaft to be propelled and repelled as desired when the hand wheel is rotated and ratchet means arranged to lock the hand wheel against rotation when the flyer unit is being rotated.

4. In twisting apparatus comprising a rotatable flyer for twisting a plurality of conductors together to form a composite core when said flyer is rotated, means provided on the flyer for advancing the conductors to the flyer and a takeup reel for the composite core, the improvement which comprises a stationary center post for rotatably supporting one side of the takeup reel for the core produced by the flyer, a reel driving shaft rotatably supported on the flyer and having its free end arranged for supporting the other side of the reel and for locking the reel to the shaft for rotation therewith, means connected to the opposite end of the shaft for imparting lateral movement to the shaft so as to cause the end thereof to move toward or away from the adjacent side of the takeup reel as desired, and means associated with the lateral movement imparting means for locking said imparting means against movement during the rotation of the flyer.

5. An apparatus for rotatably supporting a takeup reel having a frustoconical bore at each end thereof on the central axis of a flyer arranged to twist a plurality of conductors together when rotated about its central axis, which comprises a pair of rotatable supports spacedly positioned along the central axis of the flyer unit for engaging the frustoconical bores of a takeup reel for the twisted conductors, means provided on one of said supports for locking the reel for rotation therewith, means for driving the support having the locking means thereon to rotate the takeup reel at a constantly decreasing speed as the twisted conductors are taken up on the reel, and means for propelling and repelling the driven support along its axis to cause said support to engage or

disengage the adjacent bore of the reel as desired.

6. An apparatus for rotatably supporting a takeup reel on the central axis of a flyer rotatable to twist a plurality of conductors together to form a composite core, which comprises a fixed center for rotatably supporting one side of the reel, a rotatable shaft having its free end arranged to support the other side of the takeup reel, said shaft being provided with means on the free end thereof for locking the reel for rotation with the shaft, variable speed driving means for rotating said shaft to rotate said reel at a constantly decreasing speed as the core is taken up thereby, means provided on the opposite end of the shaft for propelling and repelling the shaft to cause the supporting means and locking means of said shaft to selectively engage or disengage the reel as desired, and means for locking the propelling and repelling means against movement when the flyer is rotated.

7. An apparatus for rotatably supporting a takeup reel having a tapered bore provided on each end thereof in a flyer rotatable about its central axis to twist a plurality of conductors together to form a composite core, which comprises a fixed center for engaging the tapered bore provided in one end of the takeup reel, a rotatable shaft having means provided on the free end thereof for engaging the tapered bore provided in the opposite end of the takeup reel, means associated with the bore engaging end of said shaft for locking the reel to the shaft for rotation therewith, means connected to the other end of the shaft for propelling and repelling the shaft along its axis to cause the supporting means and locking means to engage or disengage the respective bore of the takeup reel as desired, means provided on the propelling and repelling means for preventing the shaft from being repelled when the flyer is rotated, and means provided on the propelling and repelling means for preventing the support on the end of the shaft from being driven into too tight an engagement with the respective tapered bore of the takeup reel.

8. An apparatus for rotatably supporting a takeup reel having a central tapered bore at each side thereof on the central axis of a flyer type strand twisting apparatus having means for de-

livering the strand to the takeup reel at a fixed rate, which comprises a rotatable center provided on one end of the flyer for engaging the central bore provided on one side of a takeup reel to be supported on the flyer, a shaft rotatably mounted at the opposite end of the flyer and having its free end arranged to engage the central bore provided in the opposite side of the reel, spring-pressed means provided adjacent to said free end of the shaft for locking the reel to the shaft for rotation therewith, means for rotating the shaft at a constantly decreasing speed as the winding diameter of the reel increases from an empty reel to a full reel, a nut rotatably mounted at the end of the shaft and threadedly engaging the end of the shaft, a hand wheel for turning the nut to propel or repel the shaft along its axis as desired, a ratchet type clutch provided between the hand wheel and the nut to permit turning of the hand wheel after the end of the shaft has fully engaged the central bore of the reel thereby preventing the end of the shaft from becoming jammed in the central bore of the reel, and means for locking the ratchet clutch after the reel is properly supported between the center and end of the shaft to prevent movement of the hand wheel when the flyer is rotated.
